UNITED STATES PATENT OFFICE.

ADOLF AEBERLI, OF TORONTO, ONTARIO, AND WILHELM DREYER, OF LACHINE, QUEBEC, CANADA.

CARBURETOR.

Application filed January 14, 1920. Serial No. 351,426.

To all whom it may concern:

Be it known that we, ADOLF AEBERLI and WILHELM DREYER, citizen of the Swiss Republic and subject of the King of Great Britain, respectively, and residents of the city of Toronto, Province of Ontario, Dominion of Canada, and town of Lachine, Province of Quebec, Dominion of Canada, respectively, have invented certain new and useful Improvements in Carburetors, described in the following specification and illustrated in the accompanying drawings, that form part of the same.

The principal objects of this invention are to enable successful use of low grade fuels in internal combustion engines, and to provide means for delivering a priming charge of high grade fuel to the engine and automatically changing from the high grade to the low grade fuel.

The principal feature of the invention consists in the novel construction and arrangement of parts, whereby a supply of high grade fuel is first conducted to the carburetor to effect the starting of the engine and upon the starting of the engine a supply of low grade fuel is conducted to the carburetor and the supply of high grade fuel is simultaneously cut off, the operation being automatically effected by the operation of a valve controlled by the pressure of the engine exhaust, and whereby the high grade fuel connection is reestablished upon the stopping of the engine.

A further important feature consists in interposing a heating medium in the path of flow of the air and fuel mixture through the carburetor.

In the drawings, Figure 1 is a plan view of our improved carburetor.

Figure 2 is a vertical sectional view through the line *a—a* of Figure 1.

Figure 3 is an elevational view of the carburetor from the intake side indicated by the letter A in Figure 1, the lower portion of the device being shown partly in mid-section.

Figure 4 is a vertical sectional view through the line *b—b* of Figure 1.

Owing to the high cost of high grade fuels it is extremely desirable that a carburetor be produced which will be capable of effecting the successful carburation of low grade fuels.

To accomplish this result it is necessary

that the temperature of the low grade fuel be raised prior to its entering the cylinder and it is also necessary that means be provided for starting the engine in order that it may become heated before the low grade fuel is introduced, so as to avoid condensation and failure to produce an explosive mixture.

In order to obtain this result we have constructed a carburetor in which the body 1 is formed with a substantially U-shaped passage 2, one end of which terminates in the air inlet opening 3, and the other end terminates in the gas discharge opening 4. The regular control throttle 5 is arranged in the discharge opening 4 and a butterfly valve 6 is arranged in the inlet passage to choke the supply of air to the carburetor for the purpose of starting.

The body 1 is provided with a threaded cylindrical portion 7 extending downwardly from the bottom of the U-shaped passage 2 and in this threaded extension is secured the valve plug 8.

The plug is threaded into the cylindrical extension and is provided with an annular shoulder 9 against which the sheet metal cup 10 which forms the inner and high grade fuel chamber is clamped, the upper edge of the cup being held secured to the underside of the circular flange 11 formed on the body 1.

The outer cup 12 is arranged upon the outer end of the valve plug and both cups are clamped against a spacing member 12' in a fluid tight joint by means of the nut 13, the upper edge of the outer cup engaging the flange 11 in a fluid tight joint.

The plug 8 and spaced 12' are formed with a transverse passage 14 connecting with the interior of the outer cup 12 and a central passage 15 leads to the needle valve orifice 16 which is offset from the centre and connects with a cup like depression 17 in the top end of the valve plug, which forms the bottom of the U passage 2 in the body.

A transverse hole 18 through the plug 8 connects with the interior of the inner cup 10 and leads to the vertical needle valve orifice 19 connecting with a cup depression 20 arranged beside the depression 17 in the top of the plug.

Needle valves 21 and 22 control the orifices 16 and 19 respectively, being threaded

into the body 1 from the top. These may be regulated to control the volume of fuel to the carburation chamber.

At the outlet side of the carburation chamber is arranged a heating chamber 23 which extends transversely of the rim of the passage 2 and a baffle wall 24 directs the flow of gas upwardly. Extending transversely across the chamber 23 is a tube 25 preferably of copper connected with the engine exhaust by a pipe 27 and presenting a heating surface against which the fuel laden air passing through the carburetor is directed. A plurality of tubes may be used in place of the tube 25 if desired. The heated zone causes the particles of heavy fuel to be volatilized and mixing with the air makes a highly combustible mixture before it enters the engine cylinders.

On the upper side of the heating chamber 23 is arranged an auxiliary air valve 28 which when the engine accelerates to high speed opens to admit a greater volume of air. This air supply may be preheated if desired by the usual methods employed, as also may the air to the inlet 3.

Within the cups 10 and 12 are arranged the floats 29 and 30 supported on pivot suspensions 31 and 32 respectively. At the side opposite to the pivot suspension of each float is arranged a needle valve, the valve 33 on the float 29 controlling the inlet of fuel to the inner cup which enters through a passage 34 and the valve 35 on the float 30 controlling the inlet of fuel to the outer cup through the passage 36.

The passage 34 connects with a passage 37 in the body 1 which leads from the high grade fuel supply connection 38 and the passage 36 connects with a passage 39 arranged parallel with the passage 37 and leads from the low grade fuel supply connection 40.

The passage 37 is intersected by a cylindrical chamber 41 which extends past the passage 39 to the chamber 41 which extends past the passage 39 to the chamber 42 at the end of the exhaust heater tube 25. Within the chamber 41 is arranged a piston valve 43 which is formed with a reduced portion 44 at the outer end and a reduced portion 45 intermediate of its length.

The intermediate portion 46 is so arranged that it closes the low grade fuel passage 39 when the high grade fuel passage 37 is wide open and it is normally held in this position by a coil compression spring 47. The high grade fuel passage to the cup 10 is thus open and the high grade fuel feeds through the passage 19 for starting and the low grade passage is closed.

When the engine is started the pressure of the exhaust passing through the heat tube 25 to the chamber 42 moves the cy-

lindrical valve against the spring 47 and gradually shuts off the high grade fuel supply, the reduced end 44 acting against an air cushion in the plug 48. Simultaneously it opens the passage 39 allowing the low grade fuel to feed to the cup 12 and to the valve orifice 16. The two grades of fuel mix in the bottom of the carburation chamber until the high grade fuel ceases to flow through the piston valve 43 cutting off the supply. The engine will then have attained a running speed and the fuel is well heated and satisfactory carburation of the heavy fuel is accomplished.

Immediately upon the stopping of the engine the exhaust pressure is released and the spring 47 returns the valve 43 to normal cutting off the low grade fuel and opening the high grade supply ready for again starting.

A carburetor such as described accomplishes a long desired result and it must be understood that many of the details may be altered without departing from the essential features.

What we claim as our invention is:

1. In a carburetor, the combination with the engine exhaust, of a high grade fuel supply, a low grade fuel supply, a valve adapted to cut off the high grade fuel supply and open the low grade supply, and means connected with the engine exhaust for conducting exhaust pressure to actuate said valve.

2. In a carburetor, a high grade fuel supply, a low grade fuel supply, a cylindrical passage intersecting said fuel supplies, a piston valve operating in said cylinder and intercepting the flow of one fuel while freeing the flow of the other, and means for conducting the exhaust pressure from the engine to said cylinder.

3. A carburetor having two separate fuel chambers, a carburation chamber connected with said separate chambers, separate passages leading to said chambers, a piston valve intercepting said separate passages adapted to cut off one of said passages and simultaneously open the other, a pressure chamber at one end of said valve connected with the engine exhaust, and means for returning the valve to normal following the cessation of the exhaust pressure.

4. A carburetor having a carburation chamber, a pair of jets opening into said chamber, separate fuel chambers connected with each of said jets, float valves in each of said chambers, separate fuel supply passages leading to said chambers, a cylindrical passage intersecting both of said passages, a piston valve operating in said cylindrical passage and having passages therein arranged so that one of said fuel passages is open while the other is closed, and one opens while the other closes, a pressure chamber

arranged at one end of said cylindrical passage connected with the engine exhaust, and a compression spring at the opposite end of said piston valve adapted to return 5 the piston upon the cessation of the exhaust.

5. A carburetor comprising, a body having a cupped carburation chamber, a plug removably secured in the bottom of said chamber, said plug having a pair of jets 10 and separate passages thereto, valves adjustably arranged in said body to regulate

said jets, a pair of cups one arranged within the other and secured to said plug, float valves arranged in said cups, passages in said body leading separately to 15 said cups, and a piston valve interposed in said passages adapted to cut off the fuel supply to one cup and simultaneously open the supply to the other.
